REFRIGERATOR SHELF

Roy A. Heim, Evansville, Ind., assignor to Servel, Inc., New York, N. Y., a corporation of Delaware

Application April 20, 1940, Serial No. 330,681

3 Claims. (Cl. 211—147)

The present invention relates to refrigerators especially of the household type, and more particularly to devices associated with the shelves of such refrigerators.

In the usual type of household refrigerator, the positions of the shelves are non-adjustably fixed, so that unusually tall commodities cannot be stored therein unless the shelves have been previously installed to accommodate these commodities. Furthermore, this fixed setting of the shelves lends itself to inefficient utilization of available storage space in the refrigerator.

One object of the present invention is to provide means for selectively adjusting the elevation of a shelf in a refrigerator. This feature of construction permits selective elevational arrangement of the shelves in accordance with the size and shape of the commodities to be stored, and in a manner to efficiently utilize the available storage space in the refrigerator.

Another object is to provide shelf adjusting means, which can be operated without removing the shelf from the refrigerator, and without removing the contents from said shelf.

Another object is to provide a shelf adjusting mechanism, which does not interfere with easy removal of the shelf from the refrigerator cabinet.

Another object is to provide shelf adjusting means, which maintains the shelf level in all positions, and which will effectively lock the shelf in adjusted position.

Another object is to provide shelf adjusting means, which can be operated by simple manipulation of a single operating member.

Another object is to provide shelf adjusting means, which can be applied to existing refrigerators without change in the construction of said refrigerators.

Another object is to provide a shelf adjusting device, which occupies a minimum amount of space, and which does not detract from the appearance of the shelf.

Another object is to provide a shelf adjusting device, which is easily accessible for cleaning purposes.

Various other objects, features and advantages of the invention will be apparent from the following particular description, and from an inspection of the accompanying drawing, in which—

Fig. 1 is a perspective of a shelf having elevational adjusting means, embodying the present invention, the shelf being shown supported

in a refrigerator indicated in fragmentary sectional perspective,

Fig. 2 is a section taken on line 2—2 of Fig. 1.

Figs. 3, 4 and 5 are detail sections taken on lines 3—3, 4—4 and 5—5 of Fig. 2 respectively, and

Fig. 6 is a perspective of the manipulable operating member of the shelf adjusting means, shown in conjunction with one of the bearing brackets, and in unlocked position for shelf adjusting operation.

In the specific form of the invention shown, a shelf 10 comprising one of a tier is supported horizontally in a refrigerator 11, which may be of the conventional household type provided with the usual inner cabinet lining 12. The shelf 10 is desirably of customary openwork construction, with a border frame bar 13 of rectangular shape, and a grating of parallel bars 14, secured to said frame bar, and is horizontally supported in the refrigerator 11 from hangers 15, affixed to and extending from its inner lining 12. These hangers 15 shown in the form of wall hooks may be similar to those now used in household refrigerators for seating shelves in fixed position.

The shelf adjusting mechanism desirably comprises an adjuster shaft 16, supported substantially centrally of and below the shelf 10, and extending substantially parallel to the grating bars 14. The ends of this adjustor shaft 16 are journaled respectively in bearing brackets 17 and 18, secured to the underside of the shelf by any suitable means as for instance by welding to the front and rear sections of the frame bar 13 respectively.

The shelf 10 is suspended from the hangers 15 by means of cables 20, wound around the adjustor shaft 16, and carrying at their outer ends catches 21, which are shown in the form of open eye hooks, and which are straddled over said hangers respectively.

Two hangers 15 on each side of the refrigerator cabinet and two cables 20 are employed, the latter extending downwardly from said hangers along the sides of the cabinet wall 12, and then horizontally along the bottom of the shelf 10 to the adjustor shaft 16 to support the weight of said shelf. Each cable 20 is shown in one piece with its intermediate section passing through a respective diametrical hole 23 in the adjustor shaft 16 as shown in Fig. 5, so that upon rotation of said shaft, the section of each cable on opposite sides of said shaft will be wound or unwound equally and simultaneously. If desired, each cable 20 may be split into two

separate sections, and the inner ends of the sections affixed to the adjustor shaft in any suitable manner for simultaneous winding or unwinding operation thereon.

In order to guide the winding of the cables 20 on the adjustor shaft 16, a pair of retaining spool flanges 24 in the form of washers are affixed to said shaft on the outer ends of its winding sections respectively. These flanges 24 may serve to confine the shaft 16 against axial movement with respect to the shelf 10, or if desired other means such as cotter pins may be employed for that purpose.

Guides 25 are provided for the sections of the cables 20 passing around the sides of the shelf 10. These guides 25 are desirably angle-shaped, and of channel cross-section, and are secured to the side sections of the frame bar 13 by any suitable means as for instance welding.

To provide against horizontal shifting of the shelf 10, bumpers 26 are desirably secured to the corners of said shelf.

The rotation of the shaft 16 for elevational adjustment of the shelf 10 is effected by manipulation of a member 27, accessible for operation from the front of said shelf, and shown in the form of a rounded handle or knob disposed below the supporting surface of the shelf. This knob 27 is coupled to the adjustor shaft 16 for rotation therewith desirably by means of an axial sleeve or hub extension 28 on said knob, slidably embracing the outer end of said shaft, and having an elongated slot 30 lengthwise thereof. A radial pin 31 in the adjustor shaft 16 extends through the slot 30 and keys the knob 27 to said shaft.

The means for locking the shelf 10 in adjusted position desirably comprises interlocking conformations between the knob 27 and the bearing bracket 17. For that purpose, the bearing bracket 17 has a flange 32 provided with an opening 33 of polygonal conformation shown of square shape, and the section 34 of the knob hub passing therethrough is of corresponding cross-section for slidable non-rotatable reception therein. The rear sleeve section 28 of the knob hub is of cylindrical shape, and of size to permit it to slide and rotate freely in the bracket opening 33.

The knob 27 is slidably retained on the adjustor shaft 16, and is urged towards the right into locked position shown in Fig. 2 by means of a coil spring 35, housed in an axial hollow 36 of said knob, and encircling an axial pin 37. This pin is anchored at its inner end to the adjustor shaft 16 desirably through the instrumentality of the key pin 31, and has affixed near the other end thereof a collar 40 serving as an abutment for the outer end of the coil spring 35.

When it is desired to change the elevational position of the shelf 10, the knob 27 is pulled outwardly against the action of the spring 35 to the position shown in Fig. 6 and indicated in dot and dash lines in Fig. 2, to slide the square locking section 34 of the knob hub out of the square opening 33. In this position, the knob 27 can be rotated to cause rotation of the adjustor shaft 16. This causes the cables 20 to wind or unwind on the adjustor shaft 16 according to the direction of rotation of the knob 27, and causes the desired change in the elevation of the shelf 10 within the full range of the space afforded, while maintaining said shelf horizontal. When the shelf 10 has reached the desired elevational position, the knob 27 is released to return said knob inwardly under the action of the spring 35 into locked position

shown in Fig. 2. The knob 27 may have to be rotated slightly to bring the square outline of the knob locking section 34 into registry with the outline of the hole 33 before said knob can slide into position, but this will not materially affect the adjusted position of the shelf.

If a more selective and accurate adjustment of the shelf 10 is desired, the number of faces on the knob locking section 34 may be increased and the opening 33 correspondingly shaped.

The adjustable shelf 10 may be supported below a fixed shelf, in which case the upper shelf may be seated upon the hangers 15 in the usual manner, to utilize one set of hangers for both shelves.

The shelf 10 of the present invention may be elevationally adjusted in accordance with the height of the provisions or commodities to be stored. Furthermore, the shelf 10 can be adjusted with respect to the other shelves, and the provisions in the cabinet arranged in such manner as to utilize a great deal more of the available storage space than is possible with fixed non-adjustable shelves.

It should be noted that the adjusting mechanism is hardly perceptible, and does not therefore detract from the appearance of the shelves. Furthermore, it does not interfere with easy removal of the shelves from the cabinet.

Also, it should be noted that an adjustable shelf of the type disclosed can be installed in any existing conventional refrigerator without the necessity of changing the construction of this refrigerator.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent is:

1. A shelf in a refrigerator cabinet, a cable winder on said shelf, said winder having means engaging means on the shelf to lock the winder against rotation when not in use, said means being disengageable to permit operation of the winder, and a sufficient number of cables to suspend the shelf in a stable position, said cables being positively connected to said winder so as to be wound and unwound by operation of said winder and extending longitudinally below the shelf and upwardly adjacent the sides thereof and adapted to be connected to supports in said refrigerator for suspending the shelf therein, said cables being located outside of the vertical upward projection of the upper surface of said shelf to leave a clear shelf surface in the refrigerator.

2. A shelf in a refrigerator, a cable winder on said shelf intermediate the ends thereof, said winder having a clutch, which clutch has means engaging means on the winder and is provided with means to engage means on said shelf for holding the winder against rotation and said clutch being disengageable to permit operation of the winder, a sufficient number of cables to suspend said shelf in a stable position, said cables being positively connected to said winder so as to be wound and unwound by operation of said winder and adapted to be connected to supports in said refrigerator for suspending the shelf therein, and said cables extending from said winder below the under side of said shelf and

thence upward adjacent the sides of the shelf to said supports to thereby cradle said shelf leaving a clear shelf surface in the refrigerator.

3. A shelf in a refrigerator, a cable winder on the under side of said shelf, said winder having an operating member at the forward edge of said shelf having means normally engaging means on said shelf to prevent rotation of said winder, said member and said second means being disengagable to permit operation of the winder, a sufficient 10

number of cables to suspend said shelf in a stable position, said cables being positively connected to said winder so as to be wound and unwound by operation of said winder and adapted to be attached to supports on side walls of said refrigerator, and said cables being located beneath said shelf and extending upward against the sides of the shelf so as to cradle the latter and leave a clear shelf surface in the refrigerator.

ROY A. HEIM.
